(57) **CLAIM**

The ornamental design for a lock housing of computer chassis as shown and described.

DESCRIPTION

FIG. 1 is a perspective view of a lock housing of computer chassis showing my new design;

FIG. 2 is a front view thereof;

FIG. 3 is a rear view thereof;

FIG. 4 is a left view thereof;

FIG. 5 is a right view thereof;

FIG. 6 is top view thereof;

FIG. 7 is bottom view thereof; and,

FIG. 8 is a perspective view thereof showing a using condition with a computer case.

The broken lines depict portions of the lock housing of computer chassis that form no part of the claimed design. The shaded surfaces and the solid lines represent the claimed portions of the design.
